UNITED STATES PATENT OFFICE.

REUBEN WARREN, OF JEFFERSON, OHIO.

BOOT-CRIMPING MACHINE.

Specification of Letters Patent No. 27,586, dated March 20, 1860.

To all whom it may concern:

Be it known that I, REUBEN WARREN, of Jefferson, in the county of Ashtabula, in the State of Ohio, have invented a new and useful Machine for Crimping Leather for Boots; and I do hereby declare that the following is a full, clear, and exact description of the construction and operation of the same, reference being had to the annexed drawings, which make a part of this specification, in which—

Figure 1, shows the machine entire except a crank in Fig. 2.

My machine as shown in Fig. 1, consists of a platform of plank A, on which I erect a frame B, B, B, in the middle of which are placed the jaws C, C. These jaws standing upon the cross pieces of the frame are adjusted by a thumb screw and bolt D, having on the bolt on each side of the jaws a piece of india rubber d, through which the bolt passes; this allows contraction and expansion so as to accommodate the different thicknesses of the leather used. The jaws are rounded at their entrance to admit the leather at first more easily and are lined on the inside with copper brass or other metal. I have also what I call a "broke" E made of brass or other metal, raised and lowered by the lever F, and attached at the ends to a movable frame or sash, G G G, which works up and down in grooves in the frame B, B, B. My "broke" is attached to a staple H on the lever F, by a pin I. This pin not only serves to raise and lower the "broke" and sash but also has upon it on each side of the "broke" a leather strap k, attached to which are brass pincers with tongues L, l, worked by thumb screws m. When the pieces of leather are prepared to be crimped it is

passed under the "broke" and the two corners are then placed in the pincers L and raised as tight as needful by means of the crank (M, Fig. 2,) applied to the pin I. The lever F, is attached at one end to a spring N, which yields so that the "broke" may work up and down perpendicularly. The other end of the lever works between two upright bars O, O. These may be raised or lowered as shown, and serve to steady the lever and hold it up by a notch or pin as at P.

To use my machine, I pass the leather under the "broke," draw up the corners, and take hold of them with the pincers L. The jaws being properly adjusted I gradually work the lever up and down, carrying the leather gradually into the jaws in the way of the wrinkles. At the same time I turn the crank M, thus raising the leather up against the "broke." This brings the leather into form gradually "coaxing," rather than forcing it into the shape required, for it is found that when leather is forced into form by a machine working too rigidly it kills the leather making it hard like iron while the same machine may leave thinner pieces not crimped at all.

What I claim as my invention and desire to secure by Letters Patent is—

The flexible jaws, bolt and thumb screw, in combination with the "broke" pincers and tongues as stated for the purpose of crimping leather only.

REUBEN WARREN.
